UNITED STATES PATENT OFFICE.

PAUL A. WAGNER, OF JERSEY CITY, NEW JERSEY.

PILE-CUTTING DEVICE.

Application filed March 13, 1923. Serial No. 624,688.

To all whom it may concern:

Be it known that I, PAUL A. WAGNER, a citizen of the United States, residing at Jersey City, in the county of Hudson and 5 State of New Jersey, have invented a certain new and useful Improvement in Pile-Cutting Devices, of which the following is a specification.

The invention relates to mechanism for 10 severing the float threads in the manufacture of corduroys and analogous pile fabrics, and the object of the invention is to provide easily operated means of simple construction for severing the threads of the 15 pile loops or floats along the central lines of the rows, by which the cutting is reliably and uniformly performed and the employment of sharpened blades, with their attendant disadvantages, is avoided.

20 The invention consists in certain novel features and details of construction and arrangement by which the above objects are attained, to be hereinafter described and claimed.

25 The accompanying drawings form a part of this specification and show the invention as applied to a loom, and adapted to cut the floats during the manufacture of the pile fabric thereon.

30 Figure 1 is a vertical section taken on a plane parallel with the direction of the warp threads, and is partly in elevation.

Figure 2 is a corresponding plan view of a portion of the cutting device, showing one 35 side of the latter only.

The remaining figures are on a greatly exaggerated scale and show details.

Figure 3 is a vertical section corresponding to a portion of Figure 1.

40 Figure 4 is a vertical section taken on the line 4-4 in Figure 3.

Figure 5 is a plan view of a pile needle serving as one of the cutting members.

Similar reference numerals indicate the 45 same parts in all the figures.

Received longitudinally in each row of pile loops or floats 10, is a relatively stationary or passive member shown as the pile needle 11 by which the floats are 50 slightly distended and the threads supported along the central line of the row. The cutting is effected by the crushing action of a moving or active member shown as the cylindrical roller 12 forcibly urged toward

and upon the pile needle and rolled or 55 oscillated alternately in opposite directions upon the threads presented as above and lying between the active and passive members. The oscillations are preferably very rapid as compared to the slow advance of 60 the floats upon the pile needles, so that each thread in its travel along the pile needle is subjected to many traverses of the roller, and complete severance of all the threads is assured, resulting in a uniformly perfect 65 product.

The mechanism by which this operation is performed may be variously constructed; as shown in the drawings, 13 is a frame attached to or forming part of the loom at 70 the breast-beam and having a bed 14 over which the fabric passes on its way to the take-up roller, not represented. 15 are pile wires woven into the floats as usual and each connected to an eye 16 at one end of a pile 75 needle 11 which is in effect a continuation thereof and lies inclosed by the row of pile loops or floats. At the opposite end of each pile needle is a loop 17 by which it is held in place by a wire 18 extending through the 80 several loops and across the frame.

On the sides of the frame are vertical cheeks or plates 19, only one of which is shown, each carrying a pair of depending links 20 pivotally connected at the lower 85 ends to a pair of transversely extending bars 21 and 22 each of which is slotted to receive the rear ends of a series of strips of steel 23, arranged side by side and extending parallel with the pile needles 11, one for 90 each of the latter and held firmly in both bars 21 and 22 by set-screws 24. The forward ends of the strips overhang the pile needles and terminate in downwardly pressing spring arms 25 extending immediately 95 above the pile needles.

The bars 21 and 22 with their strips 23 are oscillated by a pitman 26 extending from the rear bar 22 to a crank-pin 27 on a disk 28 carried by a shaft 29 and rotated rapidly by any suitable means, not shown. The throw of the crank is preferably short and as the links 20 are relatively long, the oscillations of the bars and strips take place with a negligible amount of rising and sinking movement so that the spring arms reciprocate practically in a plane.

Across the series of pile needles 11 and

beneath the spring arms 25, extends the roller 12 which is a loosely mounted cylindrical rod of steel of small diameter upon which the arms 25 exert a downward pressure and by their frictional engagement therewith rotate or oscillate it upon the pile loops or floats 10 as the latter are received and presented in the weaving process.

The loose roller is confined within limits 10 determined by the downwardly curved hooks 30 at the ends of the arms and the pins 31 set in the arms at a prescribed distance from the hooks. The roller extends approximately at a right angle to the 15 needles, and the hooks 30 and pins 31 maintain it in this position.

The shape of the pile needle 11 in cross-section may be circular or other form adapted to present a narrow line or face to the 20 action of the roller, but the triangular form shown is preferred for the reason that it offers a wide base in contact with the upper face of the fabric within the floats and thus distributes the pressure over a large area of 25 the body of the fabric in the transfer of the pressure to the bed 14, and for the further reason that the pile needle thus shaped maintains its position on the central line of 30 the row of pile loops or floats and resists successfully any tendency to twist or roll within the pile loops or floats.

The needles may be very small and the strips 23 and arms 25 very thin and mounted closely together to operate on goods having 35 narrow rows of pile loops or floats. And the roller 12 may be a flexible steel wire of small diameter. The needles should be hard steel.

To compensate for slight inequalities or 40 irregularities in thickness of the body of the fabric and impart a degree of resilience to the bed 14 the latter is provided with a thin pad 32 of sheet rubber located beneath the needles.

The downward pressure of the spring arms 45 25 may be very slight provided the reciprocations are correspondingly rapid, and very little power is required to operate the device. The cutting is eminently reliable and is not dependent upon the sharpness of the 50 needle edge; as above stated, the device operates successfully with cylindrical needles having no defined edge other than the narrow surface line upon which the roller impinges.

55 I claim:

1. In a device of the character set forth, a 60 passive member adapted to lie within a line of pile loops, an active member in rolling contact with said passive member, and means for rolling said active member upon said passive member to sever the pile loop threads presented on said passive member.

2. In a device of the character set forth, a 65 passive member adapted to lie within a line of pile loops, an active member in rolling

contact with said passive member, resilient means acting upon said active member to press the latter into such contact, and means for rolling said active member upon said passive member to sever the pile loop threads 70 presented on said passive member.

3. In a device of the character set forth, a 75 passive member adapted to lie within a line of pile loops, an active member in rolling contact with said passive member, resilient means in frictional contact with and acting upon said active member to press the latter into such contact, and means for reciprocating said resilient means.

4. In a device of the character set forth, a 80 bed supporting the fabric to be treated, a needle received in a line of pile loops on said fabric and supported by the body thereof, a roller in contact with said needle, and means for rolling said roller upon said 85 needle.

5. In a device of the character set forth, a 90 bed, a resilient pad thereon supporting the fabric to be treated, a needle received in a line of pile loops on said fabric and supported by the body thereof, a roller in contact with said needle, and means for rolling said roller upon said needle.

6. In a device of the character set forth, a 95 pile needle adapted to lie within a line of pile loops, a roller arranged transversely of said needle and in rolling contact therewith, an arm in frictional contact with said roller and arranged to press the latter upon said needle, and means for reciprocating said 100 arm.

7. In a device of the character set forth, a 105 pile needle adapted to lie within a line of pile loops, a roller arranged transversely of said needle and in rolling contact therewith, a resilient arm in frictional contact with said roller and exerting its force to press said roller upon said needle, and means for reciprocating said arm.

8. In a device of the character set forth, 110 a series of needles adapted to lie within a series of lines of pile loops, a roller arranged transversely of said needles and in rolling contact therewith, a series of resilient arms each in frictional contact with said roller and exerting its force to press said roller upon said needles, and means for reciprocating said series of arms.

9. In a device of the character set forth, 115 a needle adapted to lie within a line of pile loops and having an angular upper edge, a roller in rolling contact with such edge, and means for pressing said roller upon said needle and moving it relatively thereto.

10. In a device of the character set forth, 120 a bed supporting the fabric to be treated, a needle received within a line of pile loops on said fabric and having a plane lower face lying upon the body of said fabric and an angular upper edge, a roller in rolling 125

contact with such edge, and means for pressing said roller upon said needle and for moving it relatively thereto.

11. In a device of the character set forth, 5 a bed, a resilient pad thereon supporting the fabric to be treated, a series of needles received in a series of lines of pile loops on said fabric and supported by the body thereof, a roller arranged transversely of said 10 needles and lying loosely thereon, a series of resilient arms arranged parallel with said needles and each in frictional contact with and upon said roller and exerting its force to press said roller upon said needles, means

for reciprocating said series of arms, and 15 means for limiting the rolling movement of said roller.

12. In a device of the character set forth, a needle adapted to lie in a line of pile loops and having an eye engaged by a pile-wire 20 in such line, a roller arranged transversely of said needle and in rolling contact therewith, and means for pressing said roller upon said needle and for moving it relatively thereto.

In testimony that I claim the invention 25 above set forth I affix my signature.

PAUL A. WAGNER.
